BOOK END

Charles E. Weyll, Jr., P.O. Box 62,
Glen Cove, N.Y. 11542

Filed July 8, 1969, Ser. No. 18,112

Term of patent 14 years

Int. Cl. D6—01

U.S. Cl. D33—3

FIG. 1 is a side elevational view of a book end, showing my new design;

FIG. 2 is a rear elevational view;

FIG. 3 is a top plan view;

FIG. 4 is a side elevational view taken from the side opposite to that in FIG. 1; and

FIG. 5 is a rear perspective view on an enlarged scale.

The undisclosed front face of the book end is conventionally flat and unornamented.

I claim:

The ornamental design for a book end, as shown and described.
